UNITED STATES PATENT OFFICE.

WILLIAM J. CURTIS, OF PHILADELPHIA, PENNSYLVANIA.

ADJUSTABLE SUPPORT FOR BEDS.

1,092,698.

Specification of Letters Patent.

Patented Apr. 7, 1914.

Application filed December 26, 1913. Serial No. 808,870.

To all whom it may concern:

Be it known that I, WILLIAM J. CURTIS, a citizen of the United States, residing at Philadelphia, in the county of Philadelphia and State of Pennsylvania, have invented certain new and useful Improvements in Adjustable Supports for Beds, of which the following is a specification.

This invention appertains to improvements in bedsteads and particularly to that type known more generally as invalid bedsteads in which adjustable rising sections are employed.

The primary object in view in my present device is to provide a specially formed bedstead which in actual use is designed to be entirely hidden by the bedclothes, and embodying a quickly detachable spring having the rising sections hereinbefore mentioned connected therewith, said spring being susceptible of attachment to the ordinary bedstead of this class without any alteration in its essential construction in order to procure the advantages of an adjustable element of this nature to eliminate the necessity of removing the spring from the bedstead in cleansing, as is required in most devices now in use.

More specifically speaking, it is comprehended by my invention to provide a bedstead with a spring embodying a central frame section adapted to be attached to the side rails and having connected thereto at opposite ends adjustable sections or supports, novel locking mechanism by means of which the supports are held at various inclinations being employed and comprising actuating levers connected at one end to locking levers carried by the supports and 40 which levers are adapted to be depressed by the actuating levers to permit free movement of the coöperating support.

With the above and other objects in view, this invention consists in the construction, combination and arrangement of parts all as hereinafter more fully described, claimed and illustrated in the accompanying drawings, wherein:

Figure 1 is a side elevation of a bedstead embodying my invention; Fig. 2 is a top plan view of the same; Fig. 3 is an enlarged fragmentary sectional view taken about on the line 3-3 of Fig. 2 and showing more clearly the locking mechanism in side elevation; Fig. 4 is an enlarged fragmentary sectional view taken on the line 4-4 of Fig.

1; Fig. 5 is a perspective view of a corner member for the central frame section; Fig. 6 is a side elevation of an ordinary bed construction with my improved spring attached thereto; and Fig. 7 is a view of the spring in collapsed or folded position.

Throughout the following detail description, and on the several figures of the drawings, similar parts are referred to by like reference characters.

Specifically describing my invention and referring to the drawings, the bedstead embodying the same comprises the side rails 1 having connected to their extremities the outwardly curving legs 2, the construction of said members being preferably angle iron, such as is commonly used in articles of this nature. The object of forming the legs 2 as just mentioned will be brought out more clearly in this description hereinafter. Said legs 2 are connected adjacent their lower portions with cross bars 2' while similar longitudinal bars 3 extending beneath in parallel spaced relation to the side rails, 80 connect the legs for strengthening the structure. Upon this frame or bedstead is disposed the essential feature of the invention consisting of the intermediate stationary spring section 4 and the adjustable head and foot rising sections 5, 5', and both of the last mentioned sections being identical in form the construction of one only will be described. The adjustable section or support 5 comprises a substantially U-shaped frame having the side members 6 which are connected by resilient or spring wires 7 lying approximately in the same horizontal plane as the upper surface of the stationary spring member 4. Each of the side members 6 of the support is suitably formed with a depending arm 8. The support, furthermore, is pivotally mounted upon the upper portion of a brace member 9, as shown most clearly in Fig. 4 of the drawings, there being a brace member for each side of the support which is connected to a central frame construction now to be described.

The central frame which constitutes the support for each of the rising sections 5, 5', is rectangular in form and comprises the four corner members or brackets 10, shown in detail in Fig. 5, each having an offstanding lip or flange 11 through which extends a fastening member 11', the two of said brackets on the corresponding sides of the bedstead being connected by longitudinally

extending angle bars 11^a which are disposed directly beneath the side rails 1, which side rails 1 are clamped between the bars 11^a and the flanges 11 by the fastening members 11' above referred to. The lower portion of each two of these corner brackets at opposite sides of the bedstead are connected by the transverse bars 3^a fastened to an inwardly extending lug 10' formed on each 10 of said brackets and as seen in Fig. 4 a brace member 9 is secured at one end to the transverse bar 3^a and its other end on which a side member of the support 5 is pivoted, passes through the adjacent bracket 15 near its topmost portion, being securely fastened in this position. It will thus be seen that a most rigid sub- or intermediate frame is formed, to the opposite ends of which are pivotally connected the adjustable rising sections hereinbefore described, and upon the frame is removably disposed the intermediate spring member 4 referred to, a plurality of straps or bars 3^b being preferably provided and connecting the longitudinal bars 3 to effectually support said 25 spring member.

It is to be noted that each of the brackets 10 is formed with a toothed sector 10'' directly adjacent the depending arms 8 of the 30 rising sections, in the lower bifurcated terminal of each of which is pivotally secured a locking lever 12 which is curved in formation and at its free extremity terminates in a slotted enlarged portion 13. The side 35 members 6 of the support 5 are also formed with depending lugs 14 and to each of the same is pivotally connected intermediate its ends a curved actuating lever 15, the inner extremity of which is provided with a laterally 40 projecting pin or projection 16, extending into the slot of its coöperating locking lever 12, thereby providing a pin and slot connection between each actuating lever 15 and locking lever 12. Extending laterally 45 from each of the locking levers 12 is a lug or projection 17 which is adapted to engage with the teeth of the adjacent sector 10'' and thereby lock the support against downward movement. Each locking lever 50 12 is normally held in locked or engaging position with respect to its coöperating sector 10'' by means of a spring 18 one end of which is connected to the adjacent side member 6 near its pivot and the other end to 55 the locking lever approximately midway of its length.

To the outer end of each of the actuating levers 15 is secured a flexible connection 19 and to the end portion of the U-shaped support 5 and at each side of the same is pivotally secured a lever 20 one end of which is connected with the adjacent flexible connection 19. It will be seen by reference to Fig. 2 of the drawings that the levers 20, 60 pivoted intermediate their lengths have their

contiguous extremities disposed in superposed relation so as to coöperate with a grooved cam member 21 adapted to be rotated by means of a handle 22 and in the actual use of my invention it is only necessary for the operator to grasp the support 5 turning the handle 22 so as to actuate the levers 20 through the instrumentality of the cam 21, and thereby cause the actuating levers 5 to depress the locking levers 12, disengaging the projections 17 from their co-operating toothed sector. When the proper adjustment has been reached the handle 22 is rotated to its initial position and the springs 18 will then pull their coöperating locking levers upwardly into engagement with the toothed sectors 10''. It will be noted in Figs. 1 and 3 that the slots in the extremities of the locking levers are inclined downwardly and when the actuating levers 15 are pulled upwardly at their outer ends, the pins 16 will slide down the slots to cause the disengagement of the locking levers hereinbefore described.

While the bed structure as above described 90 permits of the same to be readily hidden by the bedclothes, the main function of the formation of the legs 2 is for the purpose of preventing any tilting action of the bed at its end portions, due to the placing of weight 95 upon the adjustable supports which are suspended at these end portions from a point intermediate the side rails, as hereinbefore described. It furthermore permits of ready access to the ends of the bed for the purpose 100 of manipulating the handle for operating the actuating levers to adjust said supports.

As shown most clearly in Fig. 4, the longitudinally extending bars 3 are arranged contiguous to the lower portion of the corner members 10 and these bars, one at each side of the bedstead prevent any oscillation 105 of the spring member as will be apparent.

Fig. 6 of the drawings shows the adaptability of the spring of my invention to the ordinary commercial bed upon which it may readily be attached without any change of structure. It also illustrates the ease with which the bedstead may be cleaned and kept in sanitary condition by reason of the fact 110 that the supports may be raised upwardly into any position from the horizontal, as shown in this figure. Again, as shown in Fig. 7, the supports may be folded upon the central frame section and spring member 115 into a very compact structure enabling the displacement of the spring from the bedstead with ease and also rendering the structure very compact for shipping or similar purposes.

Having thus described my invention, what is claimed as new is:—

1. In combination, a bedstead including side rails, an adjustable spring therefor comprising a central frame, the side mem- 130

- bers of which are disposed beneath the side rails aforesaid, and having supporting means extending over the side rails, fastening members on the frame coöperating 5 with the supporting means and the side rails to detachably secure the spring to the latter, and an adjustable support connected to said frame.
2. In combination, a bedstead including 10 side rails, and bar members beneath the rails, an adjustable spring therefor comprising a central frame having side members coöperating with said side rails and supporting flanges extended thereover, means for clamping the side rails between the flanges and side members of the frame for detachably securing the spring to the side rails aforesaid, the bar members of the bedstead being disposed to coöperate with the central 15 frame to prevent oscillation of the latter, adjustable supports connected to said frame, and means for holding said supports at adjusted positions extending from the frame.
3. In combination, a bedstead including 20 side rails, a foldable spring therefor comprising a central frame, and adjustable end sections connected to opposite ends of said frame and adapted to be folded in superposed relation upon said frame.
4. In combination, a bedstead including 25 side rails, a foldable spring therefor comprising a rectangular frame composed of corner members, longitudinally connecting bars connected to the upper portions of the 30 corner members, transverse bars connecting the lower portions of the corner members, adjustable end sections adapted to fold upon the frame, and an intermediate spring member adapted to be disposed within the frame 35 and supported by the transverse bars aforesaid.
5. In combination, a bedstead including 40 side rails, a foldable spring therefor comprising a rectangular frame composed of corner members, said corner members being 45 formed with sectors and offstanding flanges adapted to be disposed on the side rails, upper longitudinal connecting bars adapted to coöperate with the side rails beneath the 50 same, transverse bars connecting the lower portions of the corner members, adjustable end sections adapted to fold upon the frame, and an intermediate spring section adapted 55 to be disposed within the frame and to receive the adjustable end sections when in folded position.
6. In combination, a bedstead comprising 60 side rails, an adjustable support having depending arms, locking mechanism therefor comprising toothed sectors detachably connected to the side rails with which said support is pivotally connected, locking levers

connected at one end to the arms aforesaid and engaging the toothed sectors to hold the support at predetermined adjustments, 65 actuating levers suspended from the support and having pin and slot connections at one end with the coöperating locking levers, and manipulating means for operating the actuating levers connected to their opposite 70 ends.

7. In combination, a bedstead comprising side rails, an adjustable support having depending arms, locking mechanism for holding said support at predetermined adjustments and comprising toothed sectors secured to the side rails adjacent to the depending arms aforesaid, curved locking levers connected at one end to the arms and terminating in slotted extremities at their 80 other ends, means normally holding said levers in engagement with the toothed sectors, actuating levers suspended from the support and having lateral projections extending into the slotted extremities of the 85 locking levers, and means for operating said actuating levers to cause movement of the projections in said slotted extremities and thereby depress the locking levers whereby to disengage the same from the sectors. 90

8. In combination, a bedstead comprising side rails, an adjustable support having depending arms, locking mechanism for holding said support at predetermined adjustments and comprising toothed sectors detachably secured to the side rails adjacent to the depending arms of said support, curved locking levers pivotally connected at one end to the depending arms and having downwardly inclined slots formed in their other 95 extremities, said locking levers having projections extending laterally therefrom adapted to engage with the toothed sectors for locking the support in adjusted positions, the support aforesaid having depending lugs, curved actuating levers pivotally mounted intermediate their ends on the lugs, said actuating levers having projections extending laterally therefrom into the inclined slot of its coöperating locking lever, 100 manipulating means connected to the other ends of the actuating levers for operating the locking levers aforesaid, and springs connected with the support and the locking levers normally holding the projections 110 formed thereon in engagement with the coöperating toothed sector. 115

In testimony whereof, I affix my signature in presence of two witnesses.
